DEFECTIVE NEEDLE SPOTTER.

De Witt T. Van Alen and Robert W. Kordatzky, Delavan, Wis., assignors to The George W. Borg Corporation, Chicago, Ill., a corporation of Delaware

Application July 30, 1951, Serial No. 239,266.

15. Claims. (Cl. 66—157)

The present invention relates in general to knitting machines and the object of the invention is to provide a defective needle spotter which is adapted to continuously test the needles as knitting proceeds and give a warning signal or stop the machine, or both, whenever the testing operation reveals a defective needle.

In further explanation of the object of the invention, it may be stated that it was designed especially for use with a pile fabric knitting machine which comprises a circular latch needle machine such as manufactured by the Wildman Mfg. Company of Norristown, Pa., and a carding head of the type which is disclosed in the pending application of Brandt, Ser. No. 150,447, filed March 18, 1950, now Patent No. 2,710,525. The carding head takes up fibrous material, supplied in the form of a sliver or roving, and feeds the material to the needles of the knitting machine while the machine is knitting a base fabric, whereby the fibrous material is incorporated in the stitches of the base fabric and forms a pile on one side thereof. There may be a plurality of carding heads, usually four, which correspond to and immediately precede the same number of knitting stations, respectively.

Each carding head is mounted on the frame of the knitting machine with the feeding card disposed above and outside but overlapping the circular row of needles. The operation of transferring the fibrous material from the feeding card to the needles is carried out by raising the needles vertically as they approach the card, so that as the needles pass along the rotating card they penetrate into the card clothing and the fibrous material thereon and become filled with fibers which catch on the hooks of the needles and are pulled out of the mass of fibers on the card. During this operation the needles and the card clothing encountered thereby are moving in different directions and although the peripheral speed of the card is much higher than that of the needle cylinder and the teeth of the card are quite flexible the needles are subjected to severe punishment as they pass through each carding head.

In consequence of the foregoing a considerable amount of needle wear and some breakage takes place. Permanently closed or "stuck" latches are another source of trouble. A stuck latch is a latch which has been sprung past the end of the hook and has assumed a position inside the hook, making it impossible for the latch to open. A needle which is defective either because of a broken hook or a stuck latch drops stitches and produces a run in the knitted base fabric. It is desirable therefore to find and replace such defective needles as soon as possible.

According to the former practice, defective needles were detected by watching for runs as the knitted base fabric emerged beneath the needle cylinder. As soon as a run was seen the operator stopped the machine and replaced the defective needle. Since no run could be seen until the starting end of it appeared beneath the cylinder, every run would inevitably be 4 or 5 inches long before it was observed and the defective needle

5

2

replaced. Longer runs could occur if the operator became inattentive or occupied temporarily with repairs on another machine. All such runs constitute defects in the knitted base fabric and had to be repaired by hand.

The present invention solves the problem outlined in the foregoing by providing what we call a defective-needle spotter, which is adapted to detect a defective needle promptly when it becomes defective and immediately stop the machine. The complete spotter includes a mechanical and electromagnetic pickup device mounted on the frame of the knitting machine adjacent the path of the needles as they pass by, together with an electronic control circuit installed in a suitable cabinet or container adjacent the machine and cooperating with the pickup device in response to signals produced thereby to either signal the operator or stop the machine. For reasons explained it will usually be preferable to stop the machine instantly as soon as the defective needle is discovered.

The invention will be more fully described in the ensuing specification, reference being had to the accompanying drawing, in which—

Fig. 1 is a top or plan view of the pickup device as it appears when mounted on the sinker cam ring of a knitting machine;

Fig. 2 is a section on the line 2—2, Fig. 1, showing the parts included in the magnetic pickup circuit, including one of the needles of the knitting machine;

Fig. 3 is a section on the line 3—3, Fig. 1, showing the feeler member for detecting needles having stuck latches;

Fig. 4 is a view of the pickup device as seen from the bottom, or after it is rotated 180° from the position in which it is shown in Fig. 1;

Figs. 5 and 6 are partial views of a stuck latch needle and a broken needle, respectively; and

Fig. 7 is a diagrammatic circuit drawing.

Referring now to Figs. 1 to 4, inclusive, the reference character 10 indicates a part of the needle cylinder of the knitting machine, while reference character 11 indicates a part of the sinker cam ring. These parts are shown in section in Fig. 2. Since the knitting machine is well known, a considerable amount of detail has been omitted in order not to complicate the drawing. In Fig. 1 a row of needles 12 is shown but the interspersed sinkers have been left out. In Fig. 2 the sinker 14 is shown, also a needle 12, but the needles and sinkers back of the section line have been omitted. Fig. 2 also shows the sinker supporting ring 15, which surrounds the cylinder 10 and is supported on a plurality of groups of fins such as 16 which project from the periphery of the cylinder.

The various parts of the pickup device are mounted on the base 20 which preferably is a casting of some nonmagnetic metal such as brass or aluminum. This casting is about 3 inches square and $\frac{1}{2}$ inch thick and has a number of recesses and openings as shown in the drawing. It is mounted on the top of the sinker cam ring 11 by means of screws 21 and 22 as shown in Fig. 1.

The base 20 overlaps the needle cylinder 10 and has a good sized cutout 23, Fig. 1, through which some of the needles 12 can be seen. The overlapping part of the base has a recess in which the needle aligning member 24 is disposed and secured by means of screws 26 and 27. A part of the edge 25 of member 24 has the form of the arc of a circle the center of which is at the center of the needle cylinder 10, and is engaged lightly by the hooks of the needles 12 during rotation of the needle cylinder. The member 24 may be adjusted relative to the row of needles by means of the set screws 28 and 29; after loosening the screws 26 and 27.

The curved finger 30 is secured to the lower side of the base 20 by means of a screw 31, as shown in Figs. 1

and 4. This finger projects forward in the direction from which the needles approach the pickup device and has a curved lower edge which functions to depress and open any needle latch which may happen to be partly closed. The finger 30 thus insures that when each needle passes beneath the pickup device its latch will be in open position as shown in the case of latch 13 of needle 12 in Fig. 2. This does not apply of course to stuck latch needles such as the needle shown in Fig. 5.

The reference character 33 indicates a permanent magnet, preferably of alnico, and 34 indicates a pole piece made preferably of a thin steel lamination. These parts are clamped between the two clamping bars 35 and 36 by means of the screws 37 and 38 as shown in Fig. 1, the clamping bars having suitable recesses at the left hand end to receive the magnet 33. The clamping bars are made of some suitable magnetic material such as cold rolled steel. In order to mount this assembly on the base 20 a slot 60, Fig. 4, is sawed from the left hand end of the base clear through to the opening 23, the slot being substantially equal in width to the thickness of the pole piece 34. The slot is enlarged at the left by milling or other operation to receive the lower end of the magnet. After the magnet assembly is lowered into its proper position on the base 20 as shown in Fig. 2 it is secured in position by means of the screw 39 which clamps together those parts of the base which are on opposite sides of the slot.

When the complete pickup device is mounted on the sinker cam ring 11 the lower end of magnet 33 should rest on the ring, to avoid any air gap at this point. To insure that it does so the screw 39 may be loosened and the magnet pressed down firmly against the ring, after which the screw may be tightened up again. The sinker cam ring 11, the sinker ring, the sinkers, and the needle cylinder are all made of steel so that a magnetic circuit is established which extends from the lower end of magnet 33 by way of the sinker cam ring and the sinker ring and associated parts to the needle 12, for example, Fig. 2, and thence by way of the pole piece 34 and clamping bars 35 and 36 to the upper end of magnet 33. There is necessarily a small air gap between the hook of the needle 12 and the tip of the pole piece 34, so that needle 12 and other needles can pass freely past the pole piece. The air gap can be adjusted by means of the member 24. This member, made of nonmagnetic material, aligns the needles accurately and insures so far as possible that the air gap will be the same for each needle, except of course in the case of a broken needle such as shown in Fig. 6.

The reference character 40 indicates a coil of conventional construction, which surrounds the pole piece 34 and is provided with terminals which are secured beneath binding posts on the terminal strip 41. This terminal strip may be of any suitable construction, but preferably has four sets of terminals (only three are required for the electrical connections) so that an ordinary machine screw 42 can be used to secure the terminal strip to the base 20.

Referring now particularly to Figs. 3 and 4, the arrangement for detecting a stuck latch will be described. This arrangement comprises a pivoted feeler member 52 which is mounted in the recess 50 on the under side of the base 20. The pivoted mounting for member 52 comprises a screw 47 and a nut 53 having a short round shank on which the member 52 is rotatable. The screw 47 and nut 53 are insulated from the base 20 by means of an insulating washer 48, an insulating tube 49, and a sheet of insulating material 51 which lines the recess 50. A downwardly projecting part 56 formed integrally with member 52 cooperates with the adjusting screw 58 to limit the rotation of member 52 in a clockwise direction as seen in Fig. 4. The part 56 is insulated from the screw 58 in any suitable manner, as by means of an interposed sheet of insulating material 57. A spring

54 bears on the part 56 on the opposite side thereof from screw 58 and opposes rotation of member 52 in a counter-clockwise direction. This spring may be a straight piece of resilient wire having one end inserted in a hole in the wall of recess 50 and having the other end bearing against the part 56, the wire being bent at the grooved nut 53 which serves as a fulcrum to enable the spring to exert pressure against 56. The spring is insulated from the frame 20 by a bushing 59, indicated by dotted lines in Fig. 4.

The feeler member 52 which is described above is insulated from the frame at all points but is conductively connected to the screw 47 through the nut 53, and the screw 47 is connected by means of the strap 46 to the terminal set which includes the terminal 45. This terminal is grounded whenever a needle having a stuck latch passes the detecting device. For this purpose the pivoted feeler member 52 is provided with an offset extension 55 for contacting stuck latches. As seen in Fig. 3, a needle having an open latch such as the needle partly shown in this figure can pass the extension 55 without contacting it, but in the case of a needle having a stuck latch as shown in Fig. 5 the latch will engage extension 55 and ground terminal 45 as set forth. When engaged by a stuck latch the member 52 rotates on its pivot slightly against the tension of spring 54 so as to let the needle go by.

Referring now to Fig. 7, the reference character 100 represents a three phase motor which is the motor for driving one of the carding heads of the knitting machine. Each carding head has its individual driving motor and the carding heads work in parallel to drive the knitting machine. 104 designates the operating magnet and an electromagnetic starting switch which connects the motor 100 and other motors on the same machine to the three phase line comprising conductors 101, 102, and 103 and labeled AC in the drawing. The switch S is a manually operated starting switch. Relays 106 and 109 may be any suitable type of relay such as ordinary telephone

40 The tube 115 may be a type 6SJ7 pentode and is adapted to operate as an amplifier. The terminals 43 and 44 of the coil 40 are connected to the grid circuit of this tube.

45 The tubes 116 and 117 may be type 6J5 triodes or they may be the two halves of a type 6SN7 twin triode. The function of these tubes will be explained presently.

50 Direct current for the various tube circuits may be supplied by means of a rectifier (not shown) connected to the positive and negative conductors 121 and 122. A bridge across these conductors includes the resistors 124 and 125, potentiometer 126, and resistor 127. The voltage regulator tube 119, which is connected in parallel with that portion of the bridge which includes 125, 126, 55 and 127, maintains a substantially constant potential between conductors 122 and 128 which may be, for example, 105 volts. The grounded conductor 123 is connected to the junction of resistor 125 and potentiometer 126. The resistance of resistor 125 is preferably the same as that of the potentiometer 126 and resistor 127 together, so that conductor 123 is approximately 52.5 volts positive with respect to conductor 122.

60 The tube 120 may be a type 2050 Thyratron tube. The plate circuit of the tube includes the relay 109. The control grid of the tube is connected to the grounded conductor 123 by a condenser 131, the capacity of which may be .029 mf. The resistor 130 is connected in parallel with the condenser 131 and may have a value of 250 M ohms. The cathode of the tube is connected to the slider of the potentiometer 126, which is used to adjust the grid bias at the tube. The potential at the cathode may be, for example, about 28 volts negative with respect to ground. The grid is at ground potential when there is no input signal, so that the tube has a positive bias and fires when supplied with plate volt-

age. A tube of this type will fire if it has less than about 2 volts negative grid bias.

The input circuit over which tube 120 is controlled includes the condenser 137, conductor 132, and the tube 118, which may be half of a 6H6 twin diode, or similar tube. The rectifiers 133 and 134 may be any suitable type of copper oxide or selenium rectifier, as indicated, or a 6H6 twin diode can be used. These rectifiers are connected from conductor 132 to conductors 128 and 122, respectively, and limit the input signal voltage on conductor 132 in a manner and for a purpose to be described more fully hereinafter.

The operation of the invention will now be described, it being assumed for this purpose that the apparatus is installed on a pile fabric knitting machine as described herein and that the main switches which supply current to the knitting machine and to the needle spotter are closed, the knitting machine being idle, nevertheless, because the electromagnetic starting switch 104 is open. Direct current being supplied to conductors 121 and 122 at this time, the Thyratron tube 120 has fired and relay 109 is energized, this relay being included in the cathode plate circuit of the tube. Relay 106 is also in energized condition at this time, its circuit having been closed by relay 109.

When the operator actuates the switch S to start the machine, the plate circuit of the tube 120 is broken at 108, with the result that the tube is extinguished and relays 109 and 106 are deenergized. The relay 106 has a relay switch arm 107. The switch S also closes a circuit for the electromagnet 104 at 1071, whereupon the magnet energizes and completes a locking circuit for itself at contact 105. Electromagnet 104 also closes the switch contacts in the power line which supplies current to the motors such as 100, thereby starting the operation of the machine. After the machine has been started the operator may restore the switch S, or release it if it is a self restoring switch. The tube 120 does not fire when its plate circuit is closed at 108 because it now has a negative potential at its grid, generated by running of the machine. The manner in which the negative grid potential is generated will appear presently.

It will be recalled that the pickup device includes a magnetic circuit having an air gap through which the hooks of the needles such as 12 pass successively while the machine is running, flux being supplied to this circuit by the permanent magnet 33. The passage of each needle through the gap momentarily increases the amount of flux, with the result that an alternating current is generated in coil 40 having a frequency which depends on the rate at which the needles pass the device. If the cylinder speed is 105 ft. per minute and there are 10 needles per inch the frequency will be 210 cycles per second. The coil 40 is then tuned approximately to that frequency by condenser 140.

The output of coil 40 is applied to the grid circuit of tube 115, which operates as an efficient amplifier, producing a strong signal which is applied by way of condenser 135 to the grid of tube 116. The A. C. signal at the grid of tube 116 is somewhat irregular as regards the amplitude of successive cycles because of the fact that each cycle is produced by a different needle, but this irregularity is corrected at the following amplification stages.

The tube 116 has no grid bias and accordingly passes nearly the maximum cathode plate current with zero voltage at the grid. The positive half waves of the input signal do not much affect the current flow through the tube, therefore, and are substantially eliminated as regards any effect they might have on the current and the resulting voltage at the plate of the tube. The negative half waves, however, are strongly amplified, producing large changes in voltage at the plate, which are transmitted through the condenser 136 to the grid of tube 117 in the form of an A. C. signal of considerable amplitude.

The tube 117 has a small grid bias but is heavily over-loaded. At each positive half wave the cathode plate current becomes substantially at maximum before the peak signal voltage is reached and each negative half wave drives the grid to cutoff. The result is that the peaks of both the positive and negative half waves are eliminated as regards effecting changes in voltage at the plate of the tube, and it follows, therefore that the pulsating voltage at the plate of the tube has a square wave form and that successive cycles are of uniform amplitude independent of small variations in the output of coil 40. The elimination of the positive half waves of signal voltage at tube 116 contributes to this result.

The voltage changes at the plate of tube 117 are substantially in excess of the voltage across the voltage regulator 119, which as previously mentioned is 105 volts, but the peak to peak voltage of the A. C. signal produced at conductor 132 by coupling condenser 137 is limited to substantially 105 volts by the shunt circuits through the rectifiers 133 and 134, as will be explained briefly.

At each positive half wave there is a path for the flow of current from conductor 128 through rectifier 133 to conductor 132, but since as previously explained there is a positive potential of 52.5 volts at conductor 128 no current can flow until the voltage at conductor 132 exceeds this value. At each positive half wave, therefore, the voltage on conductor 132 rises until it reaches a value of 52.5 volts, whereupon current starts to flow through rectifier 133, and as this rectifier approximates a short circuit for current in this direction no appreciable further rise in voltage can occur.

The rectifier 134 limits the amplitude of the negative half waves of signal voltage on conductor 132 in a similar manner, as it provides a path for current flow from conductor 132 to conductor 122. The latter conductor has a negative potential of 52.5 volts with respect to ground so that no current can flow until the voltage on conductor 132 falls below this value. The conductor 122 then becomes positive with respect to conductor 132, current starts to flow, and further fall in potential at conductor 132 is prevented.

Continuing with the explanation, each negative half wave of signal voltage on conductor 132 produces a flow of current through the diode 118 to charge the condenser 131. The condenser is charged each time to a constant voltage which is approximately 52.5 volts but cannot exceed that value because of the limit imposed on the voltage at conductor 132 by the circuit through the rectifier 134. The charging of condenser 131 places a negative potential on the grid of the Thyratron 120 which is equal to the charge on the condenser, or 52.5 volts. The cathode of the tube has a negative potential of somewhere around 28 volts so that the grid has a negative potential with respect to the cathode which is more than sufficient to prevent the tube from firing.

At each positive half wave the condenser 131 partially discharges through the resistor 130, but not enough to permit the Thyratron 120 to fire. The resistance value of resistor 130 is so related to the capacity of the condenser 131 and the length of the time intervals during which it discharges that at the end of each discharging period the potential on the grid of tube 120 is still sufficiently negative with respect to the cathode to prevent the tube from firing. It may be stated, however, that each time the condenser discharges the greater part of the difference between the grid and cathode potentials is eliminated, so that a moderate increase in the duration of any discharge period will reduce the negative grid potential far enough to cause the tube to fire. The sensitivity of the circuit in this respect may be adjusted by means of the potentiometer 126, the setting of which determines the potential on the cathode of the tube.

The machine is now operating in the normal manner to knit pile fabric, all of its needles presumably being

in good condition. The operator has released the starting switch S, thus supplying plate voltage to the Thyatron 120, but the tube is prevented from firing as just explained and the machine continues to run without requiring any attention from the operator.

Assuming now that the hook on one of the needles breaks off, when this needle passes the pole piece 34 of the pickup device the flux in the magnetic circuit is not altered appreciably and one cycle is omitted from the A. C. output of the coil 40. The corresponding cycle 10 in the signal voltage at conductor 132 is of course omitted also and the condenser 131, instead of getting its regular charge at that point, continues to discharge through the resistor 130. The negative potential at the grid of the Thyatron 120 then very quickly falls low enough so 15 that the tube can fire.

When the tube 120 fires as the result of the detection of a broken needle as explained above, the relay 109 is energized, and closes a circuit for relay 106. Upon energizing, relay 106 breaks the locking circuit of the 20 electromagnetic starting switch 104 at contact 107 and the switch opens the motor circuits to stop the machine. There will be some overrun but the amount is approximately the same each time so that the operator will 25 know where to look for the broken needle, that is, a certain distance beyond the pickup device. The stopping of the machine may be sufficient to attract the attention of the operator but if desired a special signal such as 150 may be provided. The replacement of the broken needle by a new one takes only a half minute or so, and when the change is completed the machine is started up 30 again by actuation of the starting switch S.

The manner in which the machine is stopped when the latch of a needle becomes stuck will be readily understood in view of the foregoing. When the stuck latch needle passes the pickup device the latch of the needle momentarily engages the feeler member 52, thereby grounding the terminal 45 and the grid of tube 120. This causes the tube to fire, whereby relay 109 is 35 energized to stop the machine as previously explained.

While certain values of resistance, voltage, etc. have been mentioned herein it will be understood that these values have been given by way of example, to facilitate the explanation, and that the invention is not limited thereto. Nor is it to be limited to the exact mechanical 40 construction and electrical circuit arrangement shown and described herein. Modification may be made within the principles of the invention and we desire to secure protection therefore for all forms of the invention that come within the scope of the appended claims.

We claim:

1. In a knitting machine having a frame and frame-supported relatively stationary parts and a power operated rotatable cylinder having an array of hooked needles, means including a frame-supported magnet providing a magnetic circuit having an air gap through which the hooks of the needles of the knitting machine pass successively during the operation of the machine, a coil inductively related to said magnetic circuit and in which each passing needle generates a cycle of alternating current by changing the amount of flux in said circuit, electric circuit means for said coil and connected apparatus for spotting a broken needle by detecting a missing cycle, and means controlled by said apparatus for stopping the cylinder upon detection of a missing cycle.

2. In a knitting machine having relatively movable parts certain of which are arranged to provide a magnetic circuit including an air gap and another part includes a cylinder equipped with hooked knitting needles mounted so that the hooks of the needles pass successively through the gap during the operation of said machine, a magnet included in said circuit to provide a flow of magnetic flux across said gap, electrical means for starting said machine, a coil inductively related to said magnetic circuit and in which alternating current is generated by the

passage of said needles, and means controlled by said alternating current for maintaining said machine in operation independent of said starting means.

3. In a knitting machine power operated and having relatively moving parts certain of which are arranged to provide a magnetic circuit including an air gap and another part is provided with an array of operated hooked knitting needles positioned with reference to the gap so that the hooks of the needles pass successively therethrough during the operation of said machine, a magnet included in said circuit to provide a flow of magnetic flux across said gap, means for starting said machine, a coil inductively related to said magnetic circuit and in which alternating current is generated by the passage of the hooks of said needles through the gap, means for maintaining said machine in operation independent of said starting means, and means responsive to a momentary interruption in said alternating current produced by the passage of a broken needle having no hook to pass through said gap, for disabling said maintaining means and thereby stop said machine.

4. A power operated knitting machine having relatively movable parts certain of which are arranged to provide a magnetic circuit having an air gap and another part has an array of hooked knitting needles positioned whereby the hooks of the needles pass through the gap successively during the operation of the machine, a magnet for producing magnetic flux in said circuit, a coil inductively related to said circuit in which the needles passing through said air gap generate alternating current by varying the amount of said flux, means for amplifying said alternating current, a condenser, means utilizing each alternate half wave of the amplified alternating current to charge said condenser to a constant value, a shunt circuit through which said condenser partially discharges to a predetermined minimum value after each charge, and continues to discharge below said minimum unless the next alternation is induced by the hook of another needle passing through the gap, and means controlled in accordance with the value of the charge on said condenser to stop the machine if the charge falls below a value which is lower than the said minimum value.

5. In a knitting machine having hooked needles mounted for movement in a knitting operation certain parts of said knitting machine being arranged to provide a magnetic circuit having an air gap through which the hooks of the needles of the knitting machine pass successively during operation of the machine, a magnet for producing magnetic flux in said circuit, a coil inductively related to said circuit in which the needles passing through said air gap generate alternating current by varying the amount of said flux, means for amplifying said alternating current, a condenser, means utilizing each alternate half wave of the amplified alternating current to charge said condenser to a constant value, a shunt circuit through which said condenser partially discharges to a predetermined minimum value after each charge, a space discharge device maintained in nonconductive condition by the charge on said condenser, there being a conductive connection between the grid of said device and the negative terminal of said condenser, adjustable bias means adapting said device to fire if said charge falls substantially below said minimum value, a relay connected for energization responsive to firing of said device, and means responsive to energization of said relay to stop said machine.

6. A magnetic pickup device for spotting broken needles in a circular knitting machine, said machine being adapted to be maintained in power operation by an uninterrupted alternating current, said knitting machine having relatively moving parts, one of which is provided with hooked needles and certain of the other parts having means providing a magnetic circuit including a pole piece located adjacent the path of the needles of said machine and a magnet adapted to utilize the hooks of the needles to

complete said circuit when the hooks of successive regularly spaced needles pass said pole piece during the operation of said machine, and a winding inductively related to said circuit and in which an alternating current is generated due to the varying flux in the magnetic circuit as successive hooks pass said pole piece whereby a missing hook of one of said needles will provide an interruption in the alternations, and connection to pass the alternating current to maintain the operation of the machine.

7. A magnetic pickup device for spotting broken hooked needles in a circular knitting machine having a sinker cam ring and other parts of magnetic material, said device comprising a base adapted to be mounted on the sinker cam ring of said machine, and said other parts of magnetic material being arranged to provide a flux path, a magnet supported on said base with one pole in contact with said ring, said ring being magnetically connected with the needles of said machine by said other parts, a pole piece supported on said base and connected through said magnetic material to the other pole of said magnet, said pole piece having its extremity disposed adjacent the path in which the hooks of said needles travel during the operation of said machine, and a coil surrounding said pole piece in which an alternating current is generated by the passage of said hooked needles.

8. A magnetic pickup as claimed in claim 7, including a member supported on said base and having an aligning surface slidably engaged by the hooks of said needles as they approach and pass said pole piece.

9. In a knitting machine, a motor for driving said machine, an electromagnetic switch for starting said motor, a manually operated switch for closing an energizing circuit for said starting switch, a locking circuit for said starting switch to maintain the same operated independent of said manually operated switch, a relay for opening said locking circuit, apparatus for detecting a defective needle as it passes a certain point in its path during operation of the machine, a second relay energized by said apparatus upon the detection of a defective needle, and a circuit completed by energizing said second relay for energizing said first relay to break said locking circuit and stop said machine.

10. A knitting machine having relatively movable parts one of which is provided with knitting needles adapted to be actuated in a knitting operation, means including a magnet mounted to another of said parts and providing a magnetic circuit having an air gap through which portions of the needles pass successively during the operation of the machine, a coil inductively related to said magnetic circuit and in which each passing needle generates a cycle of alternating current by changing the amount of flux in said magnetic circuit, and an output circuit for the coil with electrically responsive apparatus for spotting a missing needle portion by detecting a missing cycle.

11. In a knitting machine having a multiplicity of knitting needles mounted in a part of the machine which moves with respect to another part of the machine, a magnet and means forming parts of the machine shaped to provide a magnetic flux path and an open air gap through which successively pass portions of each of the needles during the operation of the machine, a coil having an output circuit and inductively related to the magnetic flux path in which each successive needle portion passing through the gap changes the magnetic flux and generates a cycle of alternating current in said output circuit, apparatus in said output circuit responsive to a missing cycle coincident with the failure of a needle portion to pass through the gap, and means controlled by said apparatus responsive to the missing cycle to stop the machine. 70

12. In a knitting machine with a movable part having a succession of latch needles in evenly spaced arrangement, a magnetic flux circuit completing device with an air gap positioned to permit passage of at least a portion of each needle through the gap, means including a power unit for starting and running the machine, and an electrical control apparatus for said power unit including as a portion thereof a control circuit for alternating current, a coil in said control circuit inductively related to the magnetic circuit whereby the passage of needles through the gap causes the induction of an alternating current in said control circuit, said control apparatus also including means requiring an uninterrupted cycle of alternations in the current coinciding with the movement of successive needles through the gap whereby a failure of a portion of a needle to pass through the gap will stop the machine.

13. The knitting machine of claim 12 wherein the control apparatus requiring an uninterrupted cycle of alternations includes a relay switch in a circuit for the power unit and a grid controlled space discharge tube having an anode circuit for control of the relay switch, said tube having a grid circuit supplied by said alternating current whereby upon an occurrence of an interrupted cycle in said grid circuit the anode circuit will change the setting of the relay switch.

14. The knitting machine of claim 12 wherein the control apparatus requiring uninterrupted alternations includes a relay switch in the circuit for the power unit and a grid control space discharge tube having an anode circuit for control of the relay switch, the knitting machine also having a feeler positioned to contact closed latches of the needles at a point where latches of the needles are normally open, and a circuit for the feeler to connect it with the grid of the tube whereby to ground the grid through a closed latch and thereby interrupt the alternations.

15. In an apparatus of the character described, an electrical machine control circuit in which electric impulses at minimum time intervals are necessary to prevent a stoppage of the machine controlled by said circuit, a machine with relatively movable parts electrically operable and connected for control by said control circuit, certain of said relatively movable parts in the machine being equipped with a magnetically permeable flux circuit having a gap, working elements carried by another of said parts and mounted in evenly spaced relation for passage through said gap in the relative movement of the parts, a coil inductively related to said magnetic flux circuit and connected with the control circuit for feed of electric impulses at time intervals corresponding with the passage of said elements through the gap whereby a missing element will cause an elongated time interval between impulses, and power means for operating the relatively movable parts at a speed to move the elements through the gap at time intervals more frequent than said minimum time intervals when there are no missing elements.
